UNITED STATES PATENT OFFICE.

EDWIN F. HULBERT, OF MILWAUKEE, WISCONSIN, ASSIGNOR, BY MESNE ASSIGNMENTS, TO THE MASTER PACKAGE CORPORATION, OF DELAWARE.

CONTAINER.

Application filed May 22, 1925. Serial No. 32,106.

The invention relates to containers, and more particularly the method and means for securing the head to the siding for the cover or main body of the container.

5 The object of the invention is to provide a construction in which the head of the container fits within the siding and is clamped thereto by a reinforcing band of sheet metal and a metal ring cooperating 10 with said band.

The invention further consists in the several features hereinafter set forth and more particularly defined by claims at the conclusion hereof.

15 In the drawings: Fig. 1 is a view, partly in elevation and partly in section, of a container embodying the invention;

Fig. 2 is a detail sectional and perspective view showing the container parts in 20 position for attaching the head or closure;

Fig. 3 is a detail sectional view showing the apparatus with container parts in position for attaching the closure.

25 The siding 4 for the container is fibre tubing, either of pressed pulp or a number of wrappings of paper or fibre sheets, and is generally in the form of cylindrical or conical tubing. This siding preferably is shouldered, as at 5, to receive the edge of a laminated fibre head 6 having one or more of 30 the laminations 7 extending beyond the others to form a dished head which fits within the siding.

A reinforcing metal ring 8 cooperates 35 with a reinforcing metal sheathing or band 9 to tightly clamp the head and siding together and form a strongly reinforced edge. During the process of manufacture the ring 8 is placed within the dished head, and the band 9, with its upper edge 10 curved slightly inwardly, is placed around the siding, as 40 shown in Fig. 2, and these parts are held between an inner anvil or chuck 11, an outer chuck 12 and a plunger 13. Associated 45 with the plunger 13 is an annular edge-forming part or member 14, having a concave edge 15, said member 14 working between the chuck 12 and the plunger 13 and serving, on its downward pressing stroke, to curl the 50 free edge 16 of the band 9 about the ring 8, and at the same time curl the edge 17 of the flanged portion of the dished head, as well

as the outer edge portion 18 of the siding, over a part of the ring 8 and to tightly 55 clamp and compress these fibre parts between the band and the ring, as well as to cause the flat portion of the head to be tightly clamped between the shoulder 5 and the ring, as shown in section in Fig. 1.

The ring 8 associated with the reinforcing 60 band not only strengthens the edge of the container adjacent the band, but also provides an efficient grip for the sheathing curled about it and thus assists the band in firmly holding the siding and head in place. 65

While containers of this general type are usually made cylindrical or conical in shape, they may be of polygonal shape, and I therefore desire it to be understood that the terms "band" or "ring" include broadly such 70 metal sheathing and reinforcing members as would be used on polygonal shaped containers in the same way that the band 9 and ring 8 here shown are used on cylindrical or conical containers. 75

I desire it to be understood that this invention is not to be limited to any particular form or arrangement of parts except in so far as such limitations are specified in the claims. 80

What I claim as my invention is:

1. In a container, the combination with the siding, of a head fitting within said siding, a metal sheathing, and a metal ring cooperating with said sheathing and engaged thereby to clamp said head to said siding. 85

2. In a container, the combination with the siding, of a head fitting within said siding, a metal sheathing having a clamping edge, and a metal member engaging said 90 head and engaged by the clamping edge of said sheathing to clamp said head to said siding.

3. In a container, the combination of a siding, a dished head fitting within said siding, a metal sheathing fitting over said siding, a metal ring fitting within the annular portion of said head and cooperating with said sheathing to clamp said head to said siding. 95

4. In a container, the combination of siding having a shouldered end portion, a head fitting within said siding and abutting said shoulder, a metal sheathing fitting over

2
said siding, and a metal ring engaging the head and engaged by said sheathing to clamp said head to said siding.

5. In a container, the combination of siding having a head-receiving shoulder, a dished head mounted within said siding and abutting said shoulder, a metal ring disposed adjacent the annular portion of said

dished head, and a metal sheathing fitting over said siding and cooperating with said ring to clamp said siding and head between it and the ring and to clamp said head between said ring and shoulder. ¹⁰

In testimony whereof, I affix my signature.

EDWIN F. HULBERT.
